UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

AUTOMATICALLY-THREADING LOOM-SHUTTLE.

1,138,316.

Specification of Letters Patent.

Patented May 4, 1915.

Application filed September 5, 1913. Serial No. 788,842.

To all whom it may concern:

Be it known that I, ALONZO E. RHOADES, of Hopedale, in the county of Worcester and State of Massachusetts, have invented certain new and useful Improvements in Automatically-Threading Loom-Shuttles, of which the following is a specification.

The present invention relates to means to prevent the escape of the thread from the eye of an automatically threading shuttle.

While otherwise applicable in some of its characteristics, the invention is particularly directed to a shuttle having a two part cast metal threader.

In the case of the one part cast metal threaders such as have heretofore been employed in the well-known Northrop weft replenishing loom, it is impracticable to cast the threader all in one piece and still have it so constructed as to contain sufficient obstructions to the unthreading of the shuttle to insure substantial freedom from this defect which frequently results in the breakage of the thread. In accordance with the present invention the cast metal threader is made in two pieces which are held closely and interlocked together in place in the shuttle, and the mating faces of these two blocks are provided with thread passages and obstructions crossing the thread passages so as to effectively prevent the accidental unthreading while permitting automatic threading.

The present improvements are illustrated in the accompanying drawings wherein—

Figure 1 is a plan view of the eye end of an automatically threading shuttle containing the improvements. Fig. 2 is a horizontal section in the plane indicated by the line 2—2 in Fig. 3. Fig. 3 is a vertical section in the plane indicated by the line 3—3 in Fig. 1. Fig. 4 is an elevation of the mating face of the front threader block. Fig. 5 is an elevation of the mating face of the rear threader block. Fig. 6 is an elevation of the inner end of the two threader blocks when interlocked together. Fig. 7 is a front view of the two threader blocks when locked together. Fig. 8 is a horizontal section of the two interlocked blocks in the plane indicated by the line 8—8 in Fig. 6. Fig. 9 is a horizontal section of the two interlocked blocks in the plane indicated by the line 9—9 in Fig. 9. Fig. 10 is a vertical section of the two interlocked blocks in the plane indicated by the line 10—10 in Fig. 1.

To facilitate description, the eye side of the shuttle will be called the "front" side; the opposite side of the shuttle will be called the "rear" side; toward the point of the shuttle at the eye end is "out"; and the end of the threader toward the bobbin or cop retaining chamber of the shuttle is the "inner" end. Hence, "forward" is toward the front side; "rearward" is toward the rear side; "inward" is toward the shuttle chamber; and "outward" is toward the point of the shuttle at its eye end.

The threader is composed of two cast metal blocks A and B, preferably of brass. The two blocks are adapted to fit each other and are maintained in proper longitudinal relation by means of a projecting pin *a* on the front block A which fits in a hole *b* in the rear block B. Each block has a semi-circular stud C on its bottom which matches a corresponding stud on the other block. When the two blocks are locked together these studs form a circular downwardly projecting stud which fits in an aperture *c* at the bottom of the chamber D in the shuttle body into which the interlocked blocks fit. Each of the blocks has a transverse aperture *d* therein. These apertures *d* of the two blocks register with each other when the blocks are interlocked, and through them passes a transverse bolt E which united the threader (consisting of the two blocks) with the shuttle. The bolt E engages a nut F in a recess in the rear of the shuttle in the usual manner as shown in Fig. 2.

When the threader composed of the two interlocked blocks is in position in the shuttle, presents various characteristics in common with that of the shuttle of United States Letters Patent to Northrop No. 769,914, September 13, 1904. The thread is directed by the curved faces at the tops of the blocks into a longitudinal thread passage P between the mating faces of the two blocks and underneath the beak G at the outer end of the threader as the shuttle travels inwardly and away from the replenishing side of the loom. Then, when the shuttle travels in the opposite direction with the eye end leading, the thread is

guided downwardly by the downwardly and inwardly extending horn H (see Fig. 7) and beneath the depending toe I thereof, into the eye J of the shuttle (Figs. 2 and 3) which is slotted at the top for the reception of the thread in the usual manner. A guard K at the rear overhangs the outer end of the beak G. At the inner end of the threader is a rearwardly extending guard L (Fig. 6) overhanging the thread passage to aid in maintaining the thread in place. This guard has an outwardly extending hook or "leader" M, which serves to catch the thread and carry it forward on the flight of the shuttle toward the replenishing end of the loom in case the thread on its previous flight has failed to get below the beak G. The block A carries a downwardly extending and inwardly inclined metallic snubbing post N around which the thread renders in passing from the threading passage P into the eye of the shuttle, as shown in Figs. 1, 2 and 3. The outer and inner margins of the shuttle eye J are protected by snubbing posts O, O, which are of metal (but may be of porcelain or other vitreous material) around which the thread renders when the shuttle travels to and fro.

In all of the respects thus far described the threader is similar to prior structures, and in the main is like that set forth in the aforesaid Northrop Patent No. 769,914, excepting that the threader is made in two blocks instead of one, and excepting the provisions which are peculiar to the two block construction. In the former one part threader, the depending toe I of the horn H, the overlapping of the beak G and the guard K together with the extension of both across the thread passage, and the overhanging of the guard G and the inner guard L across the thread passage were relied upon to prevent the accidental outward escape of the thread. In spite of these precautionary features, the thread did escape with annoying frequency and it has been found impracticable in a threader cast in one piece to make complete provision against the escape of the thread. Accordingly, in order to further provide for maintaining the thread in place, the two part construction has been invented with its additional thread retaining characteristics.

The block A has a longitudinal rib e which fits into the corresponding groove f in the block B, as shown in Figs. 5, 6 and 10, thus aiding in interlocking the two blocks together and maintaining them in accurate position with respect to each other so that the narrow thread slits are maintained of proper width. At about the middle of the height of the two blocks the main longitudinal thread passage P, substantially circular cross section, is constituted by appropriate mating and registering recesses in the two

blocks A and B. The thread occupies this main thread passage during the normal working of the shuttle, extending out from the outer end thereof across the snubbing post N into the eye J of the shuttle. It is important that the thread should be retained within this passage without danger of escaping, while at the same time insuring the easy and automatic entrance of the thread thereinto.

As shown in Fig. 6, the thread at the inner end of the threader is directed by the midway sloping upper faces of the two blocks into a narrow slot between the inner guard L and an overhanging ledge Q on the block B. The thread enters through this narrow slot into an initial upper thread passage R. This initial thread passage R is separated from the main thread passage P by means of a rearwardly, downwardly and outwardly extending tongue S carried by the block A which extends rearwardly and outwardly beyond a forwardly extending thread director T at the inner end of the block B. This tongue S and director T are separated from each other by a narrow rearwardly and outwardly inclined throat shown in Fig. 9, which is sufficient for the downward passage of the thread into the main thread passage P. Longitudinally midway of the length of the two threading blocks, the block B has a forwardly projecting rib U which closely approaches a rearwardly projecting rib V on the block A leaving a narrow thread slit between the thread passages R and P, as shown in Figs. 9 and 10, thus affording communication between the two thread passages for the thread. Above the rib U the block B has a thread deflector W which extends forwardly and nearer the middle than the point of the guard L and extending up and down across the plane thereof. This deflector W inclines at its inner face, outwardly away from the point of the guard L, as shown in Fig. 8. The ledge Q, director T, and deflector W, all extend crosswise of the shuttle from the same side of the threader; and the guard L, and tongue S, extend crosswise of the shuttle from the other side of the threader. The guard L, and the tongue S, are located, relatively to the length of the thread passages, between the ledge Q, and director T, on the one hand and the deflector W, on the other. That is to say, the guard and tongue are outside of the ledge and director and are inside of the deflector. The guard and tongue extend crosswise sufficiently to overlap the ledge, director and deflector; that is to say, as specifically illustrated, the free ends of the guard and tongue extend rearwardly beyond the free ends of the ledge, director and deflector.

When the shuttle threads, the thread is easily directed by the downwardly and midway sloping walls of the two blocks first

- into the initial thread passage R and then into the main thread passage P. On having gained this passage P, it is practically impossible for the thread to accidentally escape. The whirl of the thread as it leaves the bobbin, is in the direction of the arrow shown in the thread passage P in Fig. 6, so that during the traverse of the shuttle there is no danger of any escape of the thread.
- 5 10 When the shuttle stops, any upward jump of the thread against the tongue S cannot cause an escape because the tongue S is shielded by the director T. If by any possible chance the thread could accidentally pass between the tongue S and the director T, it will find itself in the initial passage R and it will there be forced forwardly beneath the guard L by the forward bevel of the inner face of the deflector W so that
- 15 20 there can be no upward escape from the initial thread passage R. Moreover, the likelihood of the thread escaping into this upper or initial thread passage R is minimized by the narrowness of the slit between the ribs U and V, as well as by the narrowness and inclination of the throat between the tongue S and director T, as shown in Fig. 9. If the thread gets into the initial thread passage R, it is not only forced under the guard L, by the deflector W, but it is still further safeguarded by the narrowness of the slot between the guard L and the overhanging director Q. Also, the upward escape of the thread is further rendered difficult by the usual construction of the outer end of the threader, consisting of the downwardly inclining beak G, the overhanging guard K, and the depending toe I, of the horn H, which extends below the middle of the eye J.
- 25 30 35 40 The effect of the entire construction is to effectively prevent unthreading.
- The two blocks are provided with corresponding hooks at their inner ends to retain a friction pad Y.
- 45 I claim:
1. An automatically threading shuttle having a slotted eye and a threader composed of two cast metal blocks located within a chamber in the shuttle, said blocks being characterized by a main longitudinal thread passage communicating at its outer end with the thread eye, an initial thread passage above the main passage, longitudinal ribs, U, V, on the two threader blocks respectively projecting toward each other between the two thread passages and having a narrow longitudinal slit between them affording communication between the two thread passages, a tongue S, extending rearwardly and outwardly from the inner end of the front block between the said thread passages, a thread director T, extending forwardly from the inner end of the rear block between the two thread passages leaving a
  - 50 55 60 65 narrow rearwardly and outwardly inclined throat between it and said tongue affording communication between said thread passages, a guard L, extending outwardly and rearwardly from the inner end of the front block above the initial thread passage, a ledge Q, projecting forwardly from the rear block above said guard leaving a narrow slot between it and said guard affording an entrance to said initial thread passage, a thread deflector W, projecting forwardly from the rear block part way across the initial thread passage and beyond the outer end of said guard L, a beak G, extending rearwardly from the outer end of the front block above the initial thread passage, a guard K, extending forwardly from the rear block and overhanging said beak with a thread space between, and a horn H, extending downwardly and inwardly from said beak and having a depending toe I, extending below the middle of the thread eye and outward thereof.
2. An automatically threading shuttle having a slotted eye and a threader composed of two cast metal blocks located within a chamber in a shuttle, said blocks being characterized by a main longitudinal thread passage communicating at its outer end with the thread eye, an initial thread passage above the main passage, longitudinal ribs on the two threader blocks respectively projecting toward each other between the two thread passages and having a narrow longitudinal slit between them affording communication between the two thread passages, a tongue extending rearwardly and outwardly from the inner end of the front block between the two thread passages leaving a narrow rearwardly and outwardly inclined throat between it and said tongue affording communication between the two thread passages, a guard extending outwardly and rearwardly from the inner end of the front block above the initial thread passage, a ledge projecting forwardly from the rear block above said guard leaving a narrow slot between it and said guard affording an entrance to said initial thread passage, and a thread deflector projecting forwardly from the rear block part way across the initial thread passage and beyond the outer end of said guard.
3. An automatically threading shuttle having a threader characterized by a main longitudinal thread passage communicating at its outer end with the thread eye, an initial thread passage above the main passage, longitudinal ribs projecting toward each other between the two thread passages and having a narrow longitudinal slit between them affording communication between the two thread passages, a tongue extending rearwardly and outwardly from the front

of the threader between the said thread passages a thread director extending forwardly from the rear of the threader between the two thread passages leaving a narrow rearwardly and outwardly inclined throat between it and said tongue affording communication between said thread passages, a guard extending outwardly and rearwardly from the front of one threader above the initial thread passage, a ledge projecting forwardly from the rear of the threader above said guard leaving a narrow slot between it and said guard affording an entrance to said initial thread passage, and a thread deflector projecting forwardly from the rear of the threader part way across the initial thread passage and beyond the outer end of said guard.

4. An automatically threading shuttle having a slotted eye and a threader composed of two cast metal blocks located within a chamber in the shuttle, said blocks being characterized by a main longitudinal thread passage communicating at its outer end with the thread eye, an initial thread passage above the main passage, a tongue extending rearwardly and outwardly from the inner end of the front block between the said thread passages, a thread director extending forwardly from the inner end of the rear block between the two thread passages leaving a narrow rearwardly and outwardly inclined throat between it and said tongue affording communication between said thread passages, a guard extending outwardly and rearwardly from the inner end of the front block above the initial thread passage, a ledge projecting forwardly from the rear block above said guard leaving a narrow slot between it and said guard affording an entrance to said initial thread passage, and a thread deflector projecting forwardly from the rear block part way across the initial thread passage and beyond the outer end of said guard.

5. An automatically threading shuttle having a slotted eye and a threader composed of two cast metal blocks located within a chamber in the shuttle, said blocks being characterized by a main longitudinal thread passage communicating at its outer end with the thread eye, an initial thread passage above the main passage, a tongue extending rearwardly and outwardly from the inner end of the front block between the said thread passages, a thread director extending forwardly from the inner end of the rear block between the two thread passages leaving a narrow rearwardly and outwardly inclined throat between it and said tongue affording communication between said thread passages, a guard extending outwardly and rearwardly from the inner end of the front block above the initial thread passage, and a thread deflector projecting

forwardly from the rear block part way across the initial thread passage and beyond the outer end of said guard.

6. An automatically threading shuttle having a slotted eye and a threader composed of two cast metal blocks located within a chamber in the shuttle, said blocks being characterized by a main longitudinal thread passage communicating at its outer end with the thread eye, an initial thread passage above the main passage, a tongue extending rearwardly and outwardly from the inner end of the front block between the said thread passages, a thread director extending forwardly from the inner end of the rear block between the two thread passages leaving a narrow rearwardly and outwardly inclined throat between it and said tongue affording communication between said thread passages, and a thread deflector projecting forwardly from the rear block part way across the initial thread passage and beyond the outer end of said guard.

7. An automatically threading shuttle having a slotted eye and a threader composed of two cast metal blocks located within a chamber in the shuttle, said blocks being characterized by a main longitudinal thread passage communicating at its outer end with the thread eye, an initial thread passage above the main passage, a tongue extending rearwardly and outwardly from the inner end of the front block between the said thread passages, a thread director extending forwardly from the inner end of the rear block between the two thread passages leaving a narrow rearwardly and outwardly inclined throat between it and said tongue affording communication between said thread passages, a guard extending outwardly and rearwardly from the inner end of the front block above the initial thread passage, and a ledge projecting forwardly from the rear block above said guard leaving a narrow slot between it and said guard affording an entrance to said initial thread passage.

8. An automatically threading shuttle having a slotted eye and a threader characterized by a main longitudinal thread passage communicating at its outer end with the thread eye, an initial thread passage above the main passage, a tongue extending rearwardly and outwardly from the inner end of the threader between the said thread passages, a thread director extending forwardly from the inner end of the threader between the two thread passages leaving a narrow rearwardly and outwardly inclined throat between it and said tongue affording communication between said thread passages, and a guard extending outwardly and rearwardly from the inner end of the threader above the initial thread passage.

9. An automatically threading shuttle

- having a threader characterized by a main longitudinal thread passage communicating at its outer end with the thread eye, an initial thread passage above the main passage, a tongue extending crosswise between the said thread passages, a thread director extending crosswise between said thread passages leaving a narrow rearwardly and outwardly inclined throat between it and 5 said tongue affording communication between said thread passages, a guard extending crosswise above the initial thread passage, a ledge projecting crosswise above said guard leaving a narrow slot between it and 10 said guard affording an entrance to said initial thread passage, and a thread deflector projecting from the same side as said director and ledge part way across the initial thread passage and beyond the end of said 15 guard, said tongue and guard being located (with respect to the length of said thread 20 passages) between said director and ledge on the one hand and said deflector on the other, and said tongue and guard overlapping said director, ledge and deflector. 25
10. An automatically threading shuttle having a threader characterized by a main longitudinal thread passage communicating at its outer end with the thread eye, an initial thread passage above the main passage, a tongue extending crosswise between the said thread passages, a thread director extending crosswise between said thread 30 passages leaving a narrow throat between it and said tongue affording communication 35
- between said thread passages, and a thread deflector projecting from the same side as said director part way across the initial thread passage, said tongue being located (with respect to the length of said thread 40 45 50 55 60 passages) between and overlapping said director and deflector.
11. An automatically threading shuttle having a threader characterized by a main longitudinal thread passage communicating at its outer end with the thread eye, an initial thread passage above the main passage, a tongue extending crosswise between the said thread passages, a thread director extending crosswise between said thread 40 45 50 55 60 65 70 75 80 85 90 95 100 105 110 115 120 125 130 135
